HIRAM PERCY, MAXIM, OF HARTFORD, CONNECTICUT, ASSIGNOR TO MAXIM SILENCER COMPANY, OF HARTFORD, CONNECTICUT, A CORPORATION OF CONNECTICUT.

SILENCER.

Application filed March 23, 1922. Serial No. 546,126.

The present invention relates to silencers or mufflers such as are used in connection with gas or oil engines to reduce the noise of the exhaust or in connection with various 5 kinds of steam and pneumatic machinery for deadening the discharge or intake noises thereof.

One object of the invention is to provide a muffler or silencer of the general character 10 above mentioned which will effectively perform its function without creating back pressure.

To this end, the invention contemplates broadly the provision, in an exhaust or intake muffler, of a silencing conduit constructed and arranged to obstruct the escape of the sound waves without throttling the flow 15 of the sound propagating medium.

In carrying out this feature of the invention the silencing conduit is made to comprise at least one section, the walls of which are shaped in accordance with the principles of Venturi tube construction to provide a gradually contracting portion and 20 a gradually expanding portion, the former being arranged to discharge into the latter. As the exhaust gases pass through a conduit constructed in this manner the sound waves which strike the tapering walls of the contracting portions are reflected backwardly and are trapped and as a result only such sound waves escape as pass directly through the small end of the contracted portion without striking against the converging walls 25 thereof. By reason of the Venturi action of the expanding or diverging portion of the conduit, the velocity of the gases is increased in the restricted portion to such an extent that the volume of flow per unit of time of 30 said gases or propagating medium is not materially reduced and consequently the discharge capacity of the conduit is not reduced and no undesirable back pressure is created.

Another object of the invention is to provide, in an exhaust muffler for internal combustion engines, means whereby the "head" or advance portion of the intermittent or pulsating stream of exhaust gases will serve 40 to draw out the "tail" or rear portion of the latter, and thus to assist in scavenging the engine cylinders.

Another object of the invention is to pro-

vide certain new and useful improvements in silencers tending to simplify their construction, increase their efficiency and reduce the cost of their manufacture.

With these latter objects in view, as will appear from the following description, the invention further consists in the features of construction and in the combinations and arrangements of parts hereinafter described and claimed, the advantages of which will be apparent to those skilled in the art.

In the accompanying drawings, 65

Fig. 1 is a longitudinal sectional view of a silencer embodying one feature of the present invention;

Fig. 2 is a section on the line 2—2 of Fig. 1; 70

Fig. 3 is a view similar to Fig. 1 showing a modification of the construction illustrated therein;

Figs. 4, 5, and 6 are longitudinal sectional views of silencers embodying in alternative 75 forms certain additional features of the present invention.

Referring first to Figs. 1 and 2 of the drawings, the silencer or muffler therein illustrated consists of a conduit comprising a plurality of sections 2, each having gradually contracting portions 3 and gradually expanding portions 4 relatively arranged to produce the effect of the well-known Venturi tube upon a fluid or gas flowing therethrough. The inventor has discovered that by providing, in a silencing conduit, one or more tubular sections having converging walls as in the case of the illustrated sections 3, most of the sound waves will strike the 80 converging walls and be reflected backwardly so that they will be effectively trapped, the only sound waves finally escaping being those which pass directly through the several restricted portions of the conduit without first 85 engaging any portions of the walls thereof. It is very important in most engines and in many forms of machinery in connection with which mufflers are employed that the exhaust or discharge shall not be obstructed so as to 90 produce back pressure in the engine cylinders or pressure chambers of the machinery.

To prevent the creation of back pressure the present invention contemplates the employment, in conjunction with the contracted sections 3, of the tubular sections 4 having 95 100 105

gradually diverging side walls, the latter sections being arranged to receive the sound propagating medium directly from the small ends of the converging sections 3 and to draw said medium through said converging sections so that its flow will not be substantially retarded therein.

As the gases which carry the sound waves flow through the expanding sections 4 of the conduit these sections act in substantially the same manner as a Venturi tube to expand the stream of gas and to lower its pressure and thereby to assist in increasing the discharge capacity of the conduit. Furthermore, the noise values are spread over a much greater area and consequently their value per square inch becomes much reduced. As the gases pass through the contracting sections 3, the sound waves are reflected and the noise value of those waves which escape through the small ends of these sections bear the same relation to the noise value of the waves entering said sections as the minimum cross-sectional areas of these sections bear to 25 the maximum cross-sectional areas thereof. Thus, each time the gases enter a new contracting section, a relatively large quantity of the remaining sound waves are reflected backwardly and trapped and only a relatively small quantity are permitted to escape. Consequently by employing a sufficient number of contracting sections in the silencing conduit nearly all of the sound waves will ultimately be trapped so that the noise will 35 be practically silenced by the time the exhaust gases finally emerge from the silencer.

It will be understood that by reason of the Venturi action of the diverging sections 4, the velocity of the flow through the restricted portions of the conduit will be increased in proportion to the amount of reduction in cross-sectional area of the conduit at these points. Thus substantially the same volume per unit of time will pass 45 through said restricted portions as passes in the same time through the unrestricted portions of the conduit. Accordingly, the least possible resistance is offered to the flow of the gases, the discharge thereof is practically unretarded and no back pressure is created.

It is of course, of importance that the walls of the converging portions of the Venturi sections shall be so shaped and pitched as to reflect the sound waves to best advantage without creating too much frictional resistance to the flow of the gases in which the sound waves travel and also that the diverging portions of the Venturi sections shall be properly proportioned to produce the desired effect upon the flow of the gases.

In the modified construction shown in Fig. 3, the several Venturi sections 5 have been non-uniformly spaced in the conduit to break 65 up the resonance resulting from a series of

regularly recurring contractions and expansions in the stream of the sound propagating gases.

Fig. 4 is illustrative of a silencer which embodies another feature of the present invention. As shown, a continuous tube 6 is provided with a series of Venturi sections 7 which may be similar to those already described in connection with the Figs. 1 and 2. The tube 6, which serves as a conductor for the exhaust gases or other sound propagating medium, fits tightly within a cylindrical tube 8 to form annular compartments or chambers 9 between the enlarged portions of the tube 6, each chamber 9 being substantially gas tight except for connections through a plurality of ports 10 to the inner tube 6 at the region of lowest pressure in the respective Venturi section of said tube.

With this construction the sound waves are reflected backwardly by each converging wall portion of the tube and by reason of the shape of the succeeding diverging wall portions the flow of the gases is not materially impeded. Furthermore by reason of the low pressure which exists in the restricted portions of the Venturi sections 7, the gases in the chambers 9 are partially exhausted through the ports 10 at each pulsation of the exhaust, leaving a partial vacuum within each of said chambers. This partial vacuum in the chambers 9 "satisfies" itself from or, in other words, is relieved by the following gases. Thus the "head" of each exhaust pulsation becomes effective to "pull out the tail" thereof and thus to secure complete scavenging of the engine cylinders or other pressure chambers. The inner tube 6 may be rigidly secured in any suitable manner to the outer tube 8 or the tubes 6 and 8 may be detachably held in assembled relation by means such as a spring latch 12 which may be released to permit convenient removal of the inner tube for cleaning purposes.

A modification of the construction just described is shown in Fig. 5. In this figure the silencing conduit comprises a series of separate sections 14 each having a contracted inlet 15, an enlarged intermediate portion 16 and a contracted outlet 17. The inlet 15 of each section 14 is of somewhat larger diameter than the outlet 17 thereof and the several sections are arranged in axial alignment. The outlet of each preceding section is arranged to telescope within the inlet of each succeeding section. Thus the forward half of each section 14 and the rear half of the section 14 next in advance thereof in combination constitute a Venturi section such, in effect, as the Venturi sections in the forms of silencers heretofore described. The separately constructed sections 14 may be independently secured within an outer cylindrical tube 18 by means of screws or

rivets 19 or in any other suitable manner as by welding or crimping operations. The chambers 20 which surround the reduced portions of the Venturi sections are in communication with the interior of the exhaust conduit through annular ports 21 formed between the telescoping inlet and outlet ends of the inner tube sections 14, and thus constitute low pressure chambers corresponding to the chambers 9 shown in Fig. 4.

In Fig. 6 is shown a modification in which the silencer conduit comprises a series of sections or units 23 which correspond to the conduit sections 14 of the construction shown in Fig. 5. Each unit 23 includes, in addition to the expanding and contracting portions 24 and 25 through which the exhaust gases flow, a tube 26 which cooperates with similar tubes on other units 23 to constitute an outer cylindrical shell in which low pressure chambers 32 are formed. As shown, the outer tube 26 of each unit 23 is made integral with the contracting portion 25 while the expanding portion 24 is riveted at 27 to large end of the contracting portion 25. The tubes 26 of the several units 23 have universal joint connections with each other thus providing a muffler conduit which is flexible and may be bent to avoid obstructions or otherwise adapt itself for convenient installation. To this end each tube 26 is formed with spherically curved end portions 28 and 29, the portions 29 of each tube 26 constituting a socket for receiving the portion 28 of the adjacent tube 26 thereby forming a ball and socket joint connection between said tubes 26. The tubes 26 are made of such length as to insure that the units 23 will be arranged with their outlet and inlet ends telescoping but separated by an annular space 31 providing means of communication between the interior of the conduit and the series of annular chambers 32 which surround the conduit units 23 and have the same function as the chambers 20 of the construction shown in Fig. 5.

It will be understood that the invention may be embodied in various other forms than that shown and that many changes in the details of construction and arrangement of parts may be resorted to without departing from the spirit and scope of the invention as hereinafter claimed.

Claims:

1. A muffler for silencing the exhaust of an internal combustion engine comprising a conduit for the exhaust gases having a Venturi-like passageway therein and a chamber closed on all sides except for an opening therefrom into the restricted portion of said passageway.

2. In a muffler for silencing the exhaust of an internal combustion engine, a conduit comprising a converging section and a diverging section, said converging section

opening into said diverging section to provide a Venturi-like passageway therebetween and a chamber closed on all sides except for an opening therefrom into the restricted portion of said passageway.

3. In a muffler for silencing the exhaust of an internal combustion engine, a conduit comprising a series of alternate converging and diverging sections, each converging section opening into the next succeeding diverging section to form a series of Venturi-like passageways in said conduit, and a separate chamber surrounding each passageway, each being closed at all sides except for an opening therefrom into the restricted portion of its respective passageway.

4. A muffler for silencing the exhaust of an internal combustion engine having, in combination, a conduit for the exhaust gases comprising a converging section and a diverging section, the converging section having its contracted end telescoping within the contracted end of the diverging section and separated therefrom by an annular space, and a gas tight chamber surrounding said contracted ends and communicating with the interior of said diverging section through said annular space.

5. A muffler comprising a flexible conduit for a sound propagating medium comprising a plurality of separate longitudinal sections directly joined together by flexible joints to permit a limited amount of universal movement between adjacent sections, and said sections having passageways constructed and arranged to obstruct the passage of the sound waves.

6. A muffler comprising a flexible conduit for the sound propagating medium comprising a plurality of separate longitudinal sections directly joined together by a flexible joint to permit a limited amount of universal movement between adjacent sections, said sections combining to afford a succession of Venturi-like passages for obstructing the sound waves without throttling the flow of the sound propagating medium.

7. A muffler comprising a flexible conduit for the sound propagating medium consisting of a plurality of longitudinal sections joined together to permit a limited amount of universal movement between adjacent sections, said sections combining to afford a succession of Venturi-like passages for obstructing the sound waves without throttling the flow of the sound propagating medium, and a series of low pressure chambers communicating with the restricted portions of said passages.

8. An exhaust muffler having, in combination, a series of units each comprising diverging and converging inner conduit sections and an outer tubular section having two spherically curved portions spaced lon-

itudinally thereon, one of said curved portions on each tubular section being adapted to function as the socket member and the other of said curved portions as the ball member of a series of ball and socket joints connecting said units to provide a flexible muffler conduit, said units being constructed

and arranged to provide when assembled a muffler conduit having a succession of Venturi-like silencing passages.

10 In testimony whereof I have affixed my signature.
